FIG. 8

INVENTOR
ADOLPH POKORNY
By Paul, Paul & Moore
ATTORNEYS

UNITED STATES PATENT OFFICE.

ADOLPH POKORNY, OF ST. PAUL, MINNESOTA.

STENCILING APPARATUS.

Application filed November 6, 1922. Serial No. 599,386.

To all whom it may concern:

Be it known that I, ADOLPH POKORNY, a citizen of the Republic of Germany, resident of St. Paul, county of Ramsey, and State of Minnesota, have invented certain new and useful Improvements in Stenciling Apparatus, of which the following is a specification.

This invention relates to improvements in stenciling apparatus, such as used in stenciling cards and other suitable material, usually employed for advertising purposes, etc., and has as a specific object, to provide an apparatus of the class described, capable of receiving and firmly clamping therein, without adjustment, cards or sheets of material of various sizes.

A further object of the invention is to provide means for conveniently and quickly squaring the card upon the apparatus before being clamped therein for stenciling.

A still further object is to provide means for longitudinally guiding the stencil upon the card or material positioned in the apparatus.

Other objects of the invention will more fully appear from the following detailed description and the accompanying drawings and will be pointed out in the annexed claims.

In the drawings, there has been disclosed a structure designed to carry out the objects of the invention, but it is to be understood that the invention is not confined to the exact features shown, as various changes may be made within the scope of the claims which follow.

In the drawings:

Figure 1 is a perspective view of the apparatus showing it in its operative position;

Figure 2 is a plan view showing the means provided for centering and squaring the card upon the apparatus;

Figure 3 is a view in cross-section on the line 3—3 of Figure 2, showing the flexible guide and clamping rule raised to permit the insertion of a card;

Figure 4 is an enlarged detail view on the line 4—4 of Figure 5, showing the means provided for raising the rule to release the card;

Figure 5 is a detail view on the line 5—5 of Figure 4;

Figure 6 is a perspective detail view on the line 6—6 of Figure 2, partially broken

away, showing the means provided for guiding the square longitudinally upon the apparatus;

Figure 7 is a plan view on the line 7—7 of Figure 3, showing a card in position upon the apparatus, and also showing a stencil positioned upon the card with its upper edge against the guide rule;

Figure 8 is a detail view showing one of the stencils.

In the selected embodiment of the invention illustrated in the accompanying drawings for purposes of disclosure, there is shown a stenciling apparatus comprising a bed or top plate 8, having supporting end pieces 9, preferably secured to the under side thereof, and a drawer or container 11, slidably mounted upon suitable rails 12, preferably secured to the inner sides of the end pieces 9, shown in Figure 1. This drawer provides a suitable and convenient place wherein the necessary tools, such as stencils, brushes, paints, waterpots, etc., may be stored, when the apparatus is not in use, thus keeping them free from dust and eliminating the danger of becoming lost or separated from the device.

When it is desired to use the apparatus, the drawer 11 may be removed from the rails 12 and placed upon the top of the device, and secured thereto, preferably by means of the opposed angular clips 13, adapted to receive the outwardly projecting ends 14 of the drawer front. When in the above position the operator may readily and quickly select the desired stencil, numerically arranged therein, and in plain view to the eye. Suitable compartments may also be provided at each end of the drawer to receive the necessary tools, etc.

An inclined plate 15, to which the clips 13 are secured is mounted between suitable end brackets 16, preferably secured to the ends of the bed 8 by suitable means such as screws 17, to provide a suitable support for the drawer 11, when in the position shown in Figure 1. A horizontal plate 18 is also preferably mounted between the brackets 16, and has its top side provided with suitable trays 19, wherein the usual paint disks 21 and water pots 22 may be placed for the convenience of the operator. Referring to Figure 3, it will be noted that an opening 20 is provided at the rear of the apparatus between the lower rear edge of the inclined

plate 15 and the surface of the bed. By the provision of this opening, cards of indefinite length may be stenciled transversely, if desired, as the card will pass through the opening as it is moved forwardly during the process of stenciling. It will particularly be noted that the brackets 16 overhang the bed plate a considerable distance thus providing ample clearance on the bed for cards or streamers of any length which may be moved under the brackets and fed conveniently lengthwise or transversely of the table to change the position of the cards during the stenciling operation.

15. Means for holding or clamping the card or other material to be stenciled is provided, and consists of a longitudinal strip or bar 23, pivotally mounted between the end brackets 16, preferably by means of suitable pivot pins or screws 24, as shown in Figures 4 and 5. A notch or recess 25 is provided at each end of the bar 23 adapted to receive the coiled torsion springs 26, mounted upon the pivot pins 24, between the ends of the bar and the brackets 16. Each of these springs have one end secured to the bar 23 while the other end of each spring is secured to the brackets 16, in any suitable manner. A flexible guide and clamping rail or rule 27 is secured to the forward edge of the bar 23, and projects outwardly therefrom. This rule is forwardly and downwardly inclined and adapted to bear with a yielding pressure upon the card or material through the tension of the torsion springs 26, as shown in Figure 4. The rule is preferably made of thin flexible metal, thereby adapting itself to any irregularities in the surface of the card and also firmly 40 clamping the card its full width or length, depending, of course, upon the manner in which the card is placed upon the apparatus. By referring to Figure 4, it will also be noted that the rule is formed to provide a longitudinal groove 28, extending the entire length of the rule, and adapted to receive the edge of the stencil when positioned upon the card, thereby providing a guide for the stencil and also preventing it from passing under the clamping rule when placed upon the card.

Means for raising the bar 23 and rule 27 to release the card, is provided, and consists of a shaft or rod 29, rotatably mounted in suitable bearings 31, preferably integral with the end brackets 16. Sockets or recesses 32 are provided in each end of the bar 23, adapted to receive a pair of suitable eccentrics 33, mounted upon the shaft 29, adjacent each end bracket. A flat surface 34 is provided in the upper portion of each recess 32, adapted to be engaged by the eccentrics 33, upon rotation of the shaft 29. Each eccentric is also provided with a lug 35, preferably integral therewith, and

adapted to engage shoulders 36 in each recess, to provide a suitable stop for the eccentrics when the guide rule 27 is in its uppermost position, shown in Figure 3. Finger grips 37 are provided at each end of the shaft by means of which the shaft 29 may be rotated. Thus, when the guide and clamping rule 27 is in the position shown in Figure 4, and it is desired to release the card or either change its position or remove it from the apparatus, the operator will rotate either of the finger grips 37 in either one direction or the other, as desired, causing the eccentrics 33 to engage the surfaces 34, thereby raising the bar 23 and rule 27, until the lugs 35 engage the shoulders 36.

Another important feature of this novel apparatus resides in the means provided for centering and squaring the card upon the device with reference to the guide and clamping rule 27. A straight edge slide or square 38, preferably formed of sheet metal, is adjustably and slidably mounted upon the bed 8, by means of depending flanges 39, adapted to be received by correspondingly spaced parallel grooves 41, provided in the top surface of the bed, adjacent its forward edge. The flanges 39 are preferably integrally formed with the raised portion or body of the square, as particularly shown in Figure 6, and are arranged at substantially right angles with reference to the longitudinal center line of the square. Opposed longitudinal flanges 42 are provided upon each side of the square, and project outwardly therefrom in a horizontal plane and are adapted to slide along the surface of the bed 8 when the square is moved thereon. The square is also provided with vertical side walls 43, arranged in parallel relation, against which the card or sheet of material to be stenciled is placed to be squared, as clearly indicated in Figure 7.

Referring to the above figure, and also to Figure 2, it will be noted that a portion of the horizontal flanges 42 is cut away adjacent the inner end of the square, thereby providing opposed outwardly extending lugs 44. The flanges 42 and lugs 44 are adapted to rest upon the surface of the bed 8, and functions in preventing the card or other material from slipping under the square when placed thereagainst.

Means for centering the card upon the bed 8 is shown in Figures 2 and 7. A centering mark 45, preferably in the form of an arrow, is inscribed in the top surface of the bar 23, an equal distance from each end of the apparatus. A centering or master scale 46, preferably of wood, is provided beneath this arrow and is preferably imbedded or inlaid in the surface of the bed, as shown in Figure 3, thus providing a smooth surface over which the card may slide without interference. This master scale has a plurality of

individual scales, preferably three in number, inscribed thereon, and also a line, hereinafter referred to, as the "top of type line."

The upper scale 47 is preferably numbered 5 from right to left while the middle scale 48 is arranged in reversed relation, numbering from left to right. These scales may be divided into any number of equal divisions, as desired, and may also be arranged in reverse relation to that shown, i. e., the upper scale numbering from left to right and the middle scale from right to left. The "top of type line" is represented by a heavy broken line 49, also inscribed in the surface of the master scale 46. This line is spaced a fixed distance from the bottom of the groove 28, when the rule 27 is in its clamping position, said distance corresponding to the distance between the edge of the stencil and the top of the type or character provided therein, as clearly indicated by the light dotted line in Figure 7. A third or lower scale 51 is also provided and is preferably graduated in such a manner as to correspond to cards 25 of standard widths, usually ranging in sizes from $5\frac{1}{2}$ " and upward. The stencil S also has letter indexes 52 thereon arranged in the upper and lower corners thereof to enable the user to determine where to begin the first 30 letter on the card so that the inscription, when finished will be uniformly centered.

Operation.—The operation of this apparatus may be explained in the following manner with reference to Figure 7.

35 The card or sheet of paper to be stenciled is placed upon the bed 8 and centered thereon by means of the scales 47 and 48. This is accomplished by moving the card along on the bed until the two ends of the card will 40 register correspondingly upon the scales 47 and 48, or will register like numerals, as is clearly indicated in the above figure. The square 38 is then moved up to the card until the end of said card engages one of the vertical walls 43 of the square, the flange 42 and lug 44 passing under the card as shown. As 45 soon as the card has been centered and squared as above described, the bar 23 will be released by means of the finger grips 37 and the guide and clamping rule 27 will engage the surface of the card, thereby firmly holding it in the proper position.

The operator will then select the desired 55 stencil and place it upon the card with its upper edge bearing against the bottom of the groove 28. As soon as the operator has computed the number of letters to be stenciled in a line, including spaces, etc., he will place the stencil upon the card, as 60 above described, with the numeral in the index 52, corresponding to the number of letters in the line to be stenciled, directly beneath the point of the arrow, as indicated in Figure 7. In this figure it will be 65 noted that the numeral 8 is in line with

the arrow, indicating that eight letters or characters will be required to complete the line. When the stencil is in the above position, the operator will place a small mark 53 upon the card, using the end of the 70 stencil as a guide. This is preferably done with a pencil, and represents the starting point of the first letter in the line. The stencil is then moved to the left until the nearest point of the opening in the stencil, 75 representing the desired letter, touches the mark 53. Should this be a complete letter, as in the case of the letters C and E, the entire letter may be stenciled without moving the stencil, but should it be a letter such as A or B, the diagonal or vertical portion of the letter would be stenciled first and the stencil moved to complete the letter.

Thus, by the use of this novel apparatus, 85 cards and sheets of paper or other material may be quickly and accurately stenciled without loss of time, and when completed will have the appearance of being hand painted, all letters being solid and unbroken as indicated by the word "Best" in Figure 7. 90 This device may therefore be universally used as a stenciling apparatus.

I claim as my invention:

1. A stenciling apparatus comprising a bed, a bracket projecting forwardly thereon, and beneath which the card to be stenciled is moved, a bar hinged on the forward portion of said bracket and having means for engaging and clamping a card upon said bed under said bracket.

2. A stenciling apparatus comprising a bed, a drawer slidable therein and removable therefrom, means overhanging the rear portion of said bed and spaced therefrom to allow the movement of a card on said bed, said overhanging means having means thereon to hold said drawer in an upright position thereon, and a clamp device mounted on said overhanging means for holding the article on said bed to be stenciled.

3. A stenciling apparatus comprising a bed, a bracket mounted on the rear portion of said bed and projecting forwardly thereover, a space being provided between said bracket and bed in which the article to be stenciled may be moved transversely of said bed or longitudinally thereof to permit stenciling adjustment of the article, and means pivoted on the front edge of the bracket for clamping the article during the stenciling operation.

4. A stenciling apparatus comprising a bed, a bracket mounted on the rear portion of said bed and projecting forwardly thereover, a space being provided between said bracket and bed in which the article to be stenciled may be moved transversely of said bed or longitudinally thereof to permit stenciling adjustment of the article, and means mounted on the forward portion of said

bracket and biased to press against the bed for clamping the article to be stenciled.

5. A stenciling apparatus comprising a bed having a top to receive the work, an overhanging bracket rigid with respect to the work, a clamp device attached to the front of the bracket, such clamping device having a horizontal portion adapted to extend below the stencil and to clamp the work 10 on the bed, for yieldingly holding the work to the bed, said clamp having a vertical portion against which the stencil abuts.

6. A stenciling apparatus comprising a bed having a top to receive the work, a 15 clamp device having means for yieldingly holding it on the work, and a plate mounted on said clamp device and having a guide formed therein to receive the edge of the stencil, and an extension to contact with and 20 hold the work to the bed.

7. A stenciling apparatus comprising a bed whereon the work is placed, laterally extending means for clamping the work on said bed, a vertically extending straight edge 25 slidable on said bed, and said bed having parallel slots therein for guiding said straight edge back and forth thereon.

8. A stenciling apparatus comprising a bed whereon the work is placed, means for 30 clamping the work on said bed, a straight edge perpendicular to the clamping means

and slidable on said bed and comprising a plate having downwardly projecting lugs formed thereon, and said bed having parallel adjacent slots therein to receive said 35 lugs for guiding said straight edge.

9. A stenciling apparatus comprising a bed, having oppositely reading card and centering scales extending from end to end of said bed clamping means for holding the 40 work on the bed, and scales beneath the work and extending to either side thereof indicating standard lengths of cards provided on said bed upon opposite sides of the center 45 thereof and reading toward the ends of said bed, a card guide extending over all said scales and having means to hold it continuously parallel with itself but permitting movement over the bed.

10. A stenciling apparatus comprising a 50 bed a clamp for the work, said bed having oppositely reading and centering scales thereon, a stationary indicator on the clamp, and a stencil plate having letter indexes 55 thereon cooperative with the stationary indicator for determining the proper starting point on the work of the first character to be stenciled.

In witness whereof, I have hereunto set my hand this 28th day of October 1922.

ADOLPH POKORNY.
